United States Patent Office

Des. 214,032
Patented May 6, 1969

214,032

HEXAGONAL BUILDING UNIT

Raymond V. Tackaberry, 17 Lascelles Blvd., Apt. 1610,
Toronto, Ontario, Canada

Filed Mar. 22, 1968, Ser. No. 11,187

Claims priority, application Canada Oct. 4, 1967

Term of patent 14 years

Int. Cl. D25—04

U.S. Cl. D13—1

FIG. 1

FIG. 2

FIG. 1 is a front perspective view looking towards a first wall of the design containing a front entrance; and

FIG. 2 is a rear perspective view looking towards a second wall opposite said first wall and containing a rear entrance.

The supports shown in broken lines in the drawing are for illustrative purposes only and form no part of the claimed design.

I claim:

The ornamental design for a hexagonal building unit, as shown and described.
